(57) CLAIM

The ornamental design for a saddle sleeper, as shown and described.

DESCRIPTION

FIG. 1 is a front-perspective view of an embodiment of a saddle sleeper;

FIG. 2 is a right-side view thereof;

FIG. 3 is a left-side view thereof;

FIG. 4 is a front view thereof;

FIG. 5 is a back view thereof;

FIG. 6 is a top view thereof; and,

FIG. 7 is a bottom view thereof.

The environmental structure shown in broken lines forms no part of the claimed design.
